UNITED STATES PATENT OFFICE.

YOUNG J. CHAMBLESS AND AMMIE L. LEE, OF PANAMA CITY, FLORIDA.

KNOB.

Application filed February 21, 1923. Serial No. 620,436.

To all whom it may concern:

Be it known that we, YOUNG J. CHAMBLESS and AMMIE L. LEE, citizens of the United States, residing at Panama City, in the county of Bay and State of Florida, have invented certain new and useful Improvements in Knobs, of which the following is a specification, reference being had to the accompanying drawings.

10 This invention relates to certain new and useful improvements in knobs adapted for use in anchoring wires to the walls of buildings and has particular reference to the general improvement of the type of knob 15 disclosed in United States Letters Patent No. 1,284,799, issued November 12, 1918 to Lambert J. Sindelar.

An object of the invention is to provide a knob which may be substantially firmly attached to the wall of the building before the wires are secured thereto and which may be then completely fastened in a rigid position against the wall of the building so that the wires are effectively held attached to the knob, thus enabling the anchoring of the wires to be expeditiously carried out in a most advantageous manner.

A further object of the invention is to so construct the knob as to provide seat forming grooves for the wires arranged to permit practical anchoring of wires whether they extend either perpendicularly to the wall of the building or substantially parallel therewith.

35 With the above general objects in view, and others that will be come apparent as the nature of the invention is better understood, the same consists in the novel form, combination and arrangement of parts hereinafter more fully described, shown in the accompanying drawings and claimed.

In the drawings wherein like reference characters indicate corresponding parts throughout the several views:—

45 Figure 1 is a front elevational view of a knob constructed in accordance with the present invention;

Figure 2 is a central longitudinal sectional view thereof taken on line 2—2 of 50 Figure 1;

Figure 3 is a longitudinal sectional view taken on line 3—3 of Figure 2; and

Figure 4 is a rear elevational view of the knob shown in Figure 1.

55 Referring more in detail to the drawings the present invention embodies a sub-

stantially cylindrical knob generally denoted by the numeral 5 and provided in its periphery with one or more circumferentially extending grooves 6 forming substantially circular seats spaced inwardly from the peripheral face of the body for the reception of wires in case they extend parallel with the wall of the building. As shown, the knob is provided with a flat 60 outer end and is reduced at its inner end to provide a central transverse rib 7 which extends from side to side of the body or block from which the knob is formed.

The rib 7 is provided with a flat inner 70 face adapted to flatly engage the surface of the wall to which the knob is secured, and for facilitating the attachment of the knob to the wall it is provided with an axial opening 8 to receive the usual long screw 75 which is threaded into the wall in the usual manner. The outer face of the knob is provided with a seat 9 for the head of this securing screw which seat consists merely in an enlargement of the opening 8 and 80 which allows the head of the screw to lie flush with the front face of the knob.

The grooves 6 are preferably constructed with their inner side walls flat and radially disposed and with their outer side walls 85 rounded as at 6a. The body or block is further provided with spaced parallel grooves in its periphery at opposite sides of the rib 7 so as to form substantially U-shaped seats 10 opening out at the rear 90 and side of the body. It will thus be seen that the opening 8 extends through the outer and inner ends of the block at a point intermediate the seats 10. It will also be seen that the seats 10 provide practical and convenient means for permitting the proper attachment of wires to the knob when said wires extend truly or substantially perpendicularly to the wall to which the present 95 knob is anchored.

100 As the rib 7 will engage the wall of the building with the portions of the inner face of the block at opposite sides of said rib held spaced from the wall, the fastening screw for the knob may be firmly screwed 105 into the wall prior to the engagement of the wires in the U-shaped seats 10. In this way the hands of the person installing the knob are free to then more tightly fasten the knob in place by operation of the screw 110 because of the fact that he does not have to support or hold the wires at this time,

due to their previous attachment to the knob and the firm attachment of the latter to the wall.

From the foregoing description it is believed that the construction and operation as well as the advantages of the present invention will be readily understood and appreciated by those skilled in the art.

Minor changes may be made without departing from the spirit and scope of the invention as claimed.

What is claimed is:—

A wire anchoring knob of the character described comprising a body of insulating material cylindrical in general contour and formed axially with an opening for the passage of a securing element for mounting the body upon a support, the inner end

of the body being formed with spaced parallel transverse grooves defining a central rib and side flanges, said side flanges being cut away whereby to be spaced outwardly of the plane of the face of the rib, said body being formed with a plurality of longitudinally extending grooves in its periphery communicating with the ends of said first named grooves to define U-shaped channels for the reception of wires and the body being further formed with a plurality of peripheral grooves intersecting the longitudinal grooves.

In testimony whereof we hereunto affix our signatures.

YOUNG J. CHAMBLESS.
AMMIE L. LEE.
